United States Patent Office

Des. 229,670
Patented Dec. 25, 1973

229,670

JUG

Richard L. Platte, Ann Arbor, Mich., assignor to Hoover
Ball and Bearing Company, Saline, Mich.

Original design application May 17, 1971, Ser. No.
144,381, now Patent No. 227,078, dated June 5,
1973. Divided and this application Oct. 27, 1972,
Ser. No. 301,608

Term of patent 14 years

Int. Cl. D9—01.

U.S. Cl. D9—40

FIG. 2

FIG. 3

FIG. 1

FIG. 4

FIG. 5

FIG. 6

FIG. 1 is a top plan view of a jug showing my new design;

FIG. 2 is a side elevational view thereof;

FIG. 3 is a rear elevational view thereof;

FIG. 4 is a front elevational view thereof;

FIG. 5 is a sectional view taken on the line 5-5 of FIG. 2; and

FIG. 6 is a fragmentary elevational view of another embodiment of my new design wherein the neck only has been modified.

This application is a division of my prior application Ser. No. D. 144,381 filed May 17, 1971 now Pat. No. D. 227,078 issued June 5, 1973.

I claim:

The ornamental design for a jug, as shown and described.
